UNITED STATES PATENT OFFICE.

CHARLES E. CAMPBELL, OF LYNN, MASSACHUSETTS.

X-RAY TUBE.

1,190,104.

Specification of Letters Patent.

Patented July 4, 1916.

Application filed April 5, 1913. Serial No. 759,012.

To all whom it may concern:

Be it known that I, CHARLES E. CAMPBELL, a citizen of the United States, residing at Lynn, in the county of Essex and State of Massachusetts, have invented certain new and useful Improvements in X-Ray Tubes; and I do hereby declare the following to be a full, clear, and exact description of the invention, such as will enable others skilled in the art to which it appertains to make and use the same.

The present invention relates to Röntgen or X-ray tubes.

The objects of the present invention are to afford a more efficient support for the target and to provide for the dissipation of the heat generated at the target.

With the above objects in view, the present invention consists in the X-ray tube hereinafter described and particularly pointed out in the claims.

The drawing, which illustrates the preferred embodiment of the invention, is a longitudinal section through the X-ray tube.

In the illustrated embodiment of the invention, the glass X-ray tube has a main part or bulb 1, a target extension 2, a cathode extension 3 and an anode extension 4. The cathode 5 is supported opposite the target by a glass sleeve 6 surrounding the conducting rod 7 which is connected through the sealed-in platinum wire 8 to the cathode connecting ring 9. The anode 10 is supported by a glass sleeve 11 which surrounds the conducting rod 12 which is connected by the sealed-in platinum wire 13 to the anode connecting ring 14. A glass flange 20 is formed around the mouth of the target extension 2 and extends into the bulb portion 1 of the tube. Beyond the end of the flange 20 is the target 21 which consists of a solid copper block or body 22 with an inset 23 of tungsten in its face. The face of the target is inclined at an angle of about 45° to the direction of the cathode rays which are focused by the concave face of the cathode upon the tungsten inset 23. The tungsten, on account of its very high melting point, affords a particularly desirable surface upon which to focus the cathode rays. The target is supported primarily by means of a sleeve 25 which fits around the internal flange 20. The sleeve 25 is a split tube of spring-steel which fits tightly about and grips both the copper cathode body 22 and the flange 20 and af-

fords a very secure and rigid support for the target. Fitting within the target extension 2 is a heat conducting sleeve 30. The sleeve 30 is a split tube of copper which fits snugly within the target extension 2, extends inside of the flange 20, and fits snugly over the reduced end 31 of the target. The copper is a good conductor of heat. The heat generated by the target is conducted along the copper sleeve 30 into the target extension 2 where it is dissipated into the surrounding space. While the target is primarily supported by the steel sleeve 25, the copper sleeve 30 assists in supporting the target. Surrounding the target extension 2 is an aluminum sleeve 35. The aluminum sleeve 35 absorbs the heat radiated and conducted through the glass target extension from the sleeve 30 and dissipates the heat by radiation and by conduction to the atmosphere. In order to provide the most efficient transfer of heat from the copper sleeve 30 to the aluminum sleeve 35 and dissipation from the aluminum sleeve 35, the heat radiating and absorbing surfaces are preferably blackened. The aluminum sleeve 35 is continued beyond the end of the target extension to form a protecting cage 36 for the palladium regulating tube 37. The palladium tube 37 is soldered into a short platinum sleeve 38 which is sealed through the glass. To reduce the vacuum in the Röntgen ray tube, the palladium regulating tube 37 is heated by extraneous means, and releases hydrogen gas to lower the vacuum. The target is connected through a conducting rod 40 and the palladium tube 37 to a terminal ring 41.

The target is primarily supported by the steel sleeve 25 which, although not a good heat conductor, furnishes a strong and rigid support. The heat conducting sleeve 30 can, therefore, be made of copper which, although mechanically weaker than steel, is a much better heat conductor. This tube is particularly adapted for X-ray work requiring heavy currents. The tungsten inset withstands the heat generated by the impact of the particles which make up the cathode rays and the heat from the rigidly supported target is readily conducted along the copper tube from the bulb into the heat radiating target extension where it is dissipated.

While the preferred embodiment of the present invention has been specifically illustrated and described, it is to be understood

that the present invention is not limited to its preferred embodiment, but may be embodied in other constructions within the scope of the invention as set forth in the 5 following claims:—

1. An X-ray tube having, in combination, a glass bulb, an outwardly extending tubular target extension blown in one side of the bulb, a glass flange around the mouth of the extension integral with the bulb and projecting inwardly therefrom, a target, a supporting sleeve for the target fitting over the flange, and a heat conducting sleeve connected with the target, entirely inclosed 10 within the X-ray tube and fitting closely against the inside of the target extension so as to dissipate the heat through the glass walls of the target extension, substantially as described.
2. An X-ray tube having, in combination, a glass bulb, an outwardly extending tubular target extension blown in one side of the bulb, a glass flange around the mouth of the extension integral with the bulb and projecting inwardly therefrom, a target, a heat conducting sleeve connected with the target and fitting inside the extension, substantially as described.
3. An X-ray tube having, in combination, a glass bulb, an outwardly extending tubular target extension blown in one side of the bulb, a glass flange around the mouth of the extension integral with the bulb and projecting inwardly therefrom, a target, a steel supporting sleeve for the target fitting over the flange and resiliently clasping it, and a heat conducting sleeve connected with the target and fitting inside the extension, substantially as described.
4. An X-ray tube having, in combination,

a glass bulb, an outwardly extending tubular target extension blown in one side of the bulb, a target, a heat conductor extending from the target into the target extension for conducting heat from the target to the target extension, said heat conductor being inclosed within the X-ray tube and dissipating the heat through the glass walls of the target extension, and a heat dissipating sleeve surrounding the extension outside of the heat conductor, substantially as described. 45

5. An X-ray tube having, in combination, a glass bulb, an outwardly extending tubular target extension blown in one side of the bulb, a glass flange around the mouth of the extension integral with the bulb and projecting inwardly therefrom, a target, a heat conducting sleeve extending from the target into the target extension for conducting heat from the target to the target extension, a vacuum regulating tube sealed through the glass at the end of the target extension, and a heat dissipating sleeve surrounding the target extension and projecting beyond it to form a protecting cage for the regulating tube, substantially as described. 50

6. An X-ray tube having, in combination, a glass bulb, an outwardly extending target extension blown in one side of the bulb, a glass flange around the mouth of the extension integral with the bulb and projecting inwardly therefrom, a target, a supporting sleeve of resilient material fitting over the flange to support the target, and a heat-conducting sleeve connected with the target and fitting inside of the extension, substantially as described. 75
